CLAIM

The ornamental design for a stud fastener component, as shown and described.

DESCRIPTION

FIG. 1 is a top perspective view of a stud fastener component of one embodiment of the present invention;

FIG. 2 is a bottom perspective view of the design illustrated in FIG. 1;

FIG. 3 is a top plan view of the design illustrated in FIG. 1; FIG. 4 is a bottom plan view of the design illustrated in FIG. 1;

FIG. 5 is a front elevation view of the design illustrated in FIG. 1, the other side elevation views being the same; and, FIG. 6 is a cross-sectional view of the design illustrated in FIG. 1.
